UNITED STATES PATENT OFFICE.

ELBRIDGE J. STEELE, OF NEW HAVEN, CONNECTICUT, ASSIGNOR TO SARGENT & CO., OF SAME PLACE.

DESIGN FOR DOOR-HINGES.

Specification forming part of Design No. 7,405, dated April 28, 1874; application filed February 18, 1874.
[Term of Patent 7 years.]

CASE B.

To all whom it may concern:

Be it known that I, ELBRIDGE J. STEELE, of New Haven, in the county of New Haven and State of Connecticut, have invented a new Design for Door-Hinges; and I do hereby declare the following, when taken in connection with the accompanying drawings and the letters of reference marked thereon, to be a full, clear, and exact description of the same, and which said drawings constitute part of this specification, and represent, in—

Figure 1, a front view of one leaf; Fig. 2, a rear view of the other leaf.

This invention relates to a design for the ornamentation of the faces of the leaves of that class of hinges known to the trade as butt-hinges; and consists in the ornamentation of the faces of the hinge, as shown in the accompanying illustration, and hereinafter described.

The front face (shown in Fig. 1) is paneled, the border plain, the bed filled with tracery

of scroll-work in relief, as shown—that is to say, a pair of scrolls meeting at the center, and connected by two triangles, each of said scrolls running toward their respective ends, and terminating in a floriated larger scroll, and the said center scrolls turning up into the center, and terminating there in an ornament. The rear face, or that part of it which is exposed, is paneled, and the bed of the panel filled with tracery of foliated scroll-work in relief, branching up and down from a pair of scrolls, which meet at the center, as seen in Fig. 2.

I claim as my invention—

1. The design for the front face of door-hinges, as shown and described.
2. The design for the rear face of door-hinges, as shown and described.

ELBRIDGE J. STEELE.
